CLAIM

The ornamental design for a connector for linking an integrated system digital network adaptor to a data terminal or the like, as shown.

DESCRIPTION

FIG. 1 is a top, front, and right side perspective view of a connector for linking an integrated system digital network adaptor to a data terminal or the like showing our new design;

FIG. 2 is a top, rear, and left side perspective view thereof; and

FIG. 3 is an enlarged front elevational view thereof.
